WRITING INSTRUMENT

Robert W. Schier, Evanston, Ill., assignor to The Parker Pen Company, Janesville, Wis., a corporation of Wisconsin

Application November 24, 1958, Serial No. 53,490

Term of patent 14 years

(Cl. D74—17)

Fig. 1 is a rear elevational view of a writing instrument embodying my new design;

Fig. 2 is a side elevational view thereof;

Fig. 3 is a front elevational view thereof;

Fig. 4 is a top plan view thereof taken along lines 4—4 in Fig. 1;

Fig. 5 is a bottom plan view thereof taken along lines 5—5 in Fig. 3; and

Fig. 6 is the same view as Fig. 4, but on an enlarged scale.

The essential features of the design reside in the solid lines shown on the drawing.

I claim:

The ornamental design for a writing instrument, as shown and described.
